UNITED STATES PATENT OFFICE.

HERMAN LISSNER, OF NEW YORK, N. Y.

ADJUSTABLE WAISTBAND FOR TROUSERS.

Application filed March 27, 1926. Serial No. 97,968.

This invention relates to an adjustable waist band for trousers and it consists in the novel features hereinafter described and claimed.

5 An object of the invention is to provide a new and improved adjustable waist band for trousers and a method of sewing the waist band to a pair of ready-made trousers so that the trousers can be quickly altered at 10 the waist line to fit the wearer of the trousers.

A further object of the invention is to practice the method in such a manner that when the trousers are altered at the waist 15 line, that is made larger or smaller, the waist line will present as finished an appearance as it presented originally and before the trousers were altered at this point.

A further object of the invention is to 20 provide in the waist band at the seam which connects the side sections of the trousers together an inwardly disposed pleat reinforced by stiffening material, one side of the pleat bridging the seam and the other 25 side of the pleat having spaced edges whereby the side sections of the trousers may be folded snugly against each other thus making it possible to stack a great number of pairs of trousers upon a table flat surface 30 in approximately level condition.

A still further object of the invention is to provide a new and improved method of manufacturing and altering trousers, in which a machine can be used almost wholly 35 and which results not only in a better and neater garment but, which enables the garments to be produced by the less skilled mechanic, and then too at a saving of time, expense and efforts.

40 In the accompanying drawing:

Figure 1 is a fragmentary view showing the upper immediate portions of a pair of trousers with the improved waist band applied thereto.

45 Figure 2 is a longitudinal sectional view cut on the line 2—2 of Figure 1.

Figure 3 is an enlarged transverse sectional view cut on the line 3—3 of Figure 2.

As is well known so-called ready-made 50 trousers have to be altered at the waist line in almost every instance to fit the buyer thereof. When, therefore, the waist band is in two sections it is necessary not only to alter the trousers material to increase or 55 decrease the waist line of the trousers material, but alter the waist band with it and

then finish off the waist band to give it the finished appearance it had in the first place.

In the present invention the altering of the trousers at the waist line is greatly 60 facilitated by providing a band and method with which such an alteration can be made quicker than is possible with the old method pointed out. Furthermore, the waist band may be folded at the rear seam of the trousers so that the leg sections of the trousers may lie flat or close against each other thus 65 permitting a number of pairs of pants to be stacked in approximately level or flat condition upon a table or plane surface.

70 As illustrated in the drawing the trousers consist of side sections 1 and 2 joined together by a seam 3 which forms the rear seam of the trousers and the said section having respective folds 4 and 5 which are 75 inwardly disposed and lie at the opposite sides of the seam 3. During the process of altering the trousers the seam 3 is ripped and the folds 4 and 5 are taken up or let out as may be required and the sections are 80 rejoined by a new seam 3.

The waist band consists of a single strip 6 which is reinforced at its inner sides by a strip 7 of suitable reinforcing material. The 85 waist band and the reinforcing strip are provided with a pleat 8 which is inwardly disposed and which extends transversely across the seam 3 as best shown in Figure 2 of the drawing. The said seam lies between the intermediate portion of the waist band and 90 the inner surfaces of the trouser section 1 and 2. The pleat is provided at its outer side with spaced edges 9 so that when the intermediate portion of the pleat is folded these edges may come together and thus provide a hinge for the trousers as a whole 95 which permits the sections 1 and 2 to be folded close together by folding that portion of the pleat 8 only which extends across the seam 3 and by folding the sections 1 and 2 at the said seam 3. When the trousers are altered the pleat 8 is taken up or 100 let out as desired but the edges 9 are always positioned spaced from each other and the edges of the pleat and the strips 6 and 7 are secured to the sections 1 and 2 of the trousers by a waist seam 10 as best shown in Figure 1 of the drawing.

105 It will be observed that the trouser sections are joined together by the back seam 110 3 which is disposed transversely of the waist line of the sections and the folds 4 ex-

tend inwardly of the said trouser sections and have surfaces in direct contact with the inner surfaces of the sections. Thus, the said folds fit snugly and closely against the sections. The continuous side of the pleats 8 is disposed inwardly toward the seam 3 and lies directly against the inner surfaces of the folds 4 but is not disclosed between the folds and the sections. The edges 9 of the pleat are spaced from each other beyond the opposite sides of the seam 3 and are also spaced from the said seam by the continuous side portion of the pleat. Therefore, the trousers may be folded snugly at the seam 3 as ample clearance space is provided between the edges 9 to permit the goods to bend without bulging or buckling. At the same time the folds 4 being in direct contact with the inner surfaces of the sections 1 and 2 will permit the waist line of the trousers to fit snugly around the waist of a wearer when being worn.

From the foregoing description of the construction of my improved device, it will be seen that I have provided a simple, inexpensive and efficient means for carrying out the objects of the invention, and while I have particularly described the elements best adapted to perform the functions set forth, it is obvious that various changes in form, proportion, and in the minor details of construction may be resorted to, without departing from the spirit or sacrificing any of the principles of the invention.

Having thus described the invention, what is claimed is:

1. Trousers comprising side sections joined together by a seam disposed across the waist line, each of said sections having an inwardly disposed fold, said folds being disposed at opposite sides of the seam and with surfaces in close contact with the inner surfaces of the sections, a waist band consisting of a continuous strip of material ap-

plied along the waist line of the sections, 45 said strip being provided with a pleat which is inwardly disposed toward the seam and lies between the intermediate portion of the strip and against the adjacent surfaces of the folds and which extends transversely 50 across the seam at the meeting edges of the folds, said pleat having edge folds which lie in close contact with the intermediate portions of the pleat.

2. Trousers comprising sections joined by 55 a seam which is disposed transversely of the waist line, each of said sections having an inwardly disposed fold, said folds lying at the opposite sides of the seam and with surfaces in close contact with the inner surfaces of the sections, a waist band consisting of continuous strips of material provided at its intermediate portion with an inwardly disposed pleat which lies between the intermediate portion of the waist band and 60 the folds and which extends transversely 65 across the seam at the meeting edges of the folds, said pleat having spaced edges lying beyond the opposite sides of the seam.

3. The method of making and altering the 70 waist line of a pair of trousers which consist in sewing the sections of the trousers together at the back and with folds at the opposite sides of the seam, said folds having surfaces brought in close contact with 75 the inner surfaces of the sections, then sewing a continuous strip of waist band to the waist line of the sections of the trousers with a pleat formed in the waist band strip at the seam between the sections, said pleat 80 being inwardly disposed towards the seam and lying against the adjacent surfaces of the folds and the intermediate portion of the waist band strip and finally fixing the edges of the pleat with relation to the seam. 85

In testimony whereof I affix my signature.

HERMAN LISSNER.
